IRON

Benjamin A. Kaplan, Philadelphia, Pa.

Application November 15, 1938, Serial No. 240,579

7 Claims. (Cl. 219—25)

This invention relates to irons.

It has been proposed to manufacture an iron having a hollow body formed of translucent or transparent material in which an electric resistance element is housed and in which a vacuum is maintained to prevent the destruction of the resistance material by the oxygen of the air. In place of the vacuum being drawn in the hollow body per se, a plurality of electric lamp bulbs 5 may be housed within the transparent hollow body in an attempt to develop sufficient heat for laundering purposes. In this type of product no means, however, was employed for concentrating the light and heat rays through the flat working 10 surface of the iron so that the heat rays were radiated in all directions and the product was ineffective for the purpose.

It is an object of the present invention to provide an iron or heating device with a transparent hollow body with means for concentrating the light and heat rays directly on the work for not only illuminating the work but for creating at the flat working surface of the iron sufficient heat to accomplish the results intended.

Another object of the invention is the provision of an iron formed of a hollow transparent body in which an incandescent lamp of sufficient power is removably housed within the hollow body, a portion of the outer surface of the hollow body 20 being provided with a reflector while the inner surface of the flat working portion of the iron is provided with curved projections which will aid in concentrating the rays from the lamp at the working surface.

A further object of the invention is the provision of an iron having a transparent hollow body with cooperating reflecting surfaces and light concentrating elements whereby when an incandescent lamp of sufficient power is placed 30 within the hollow body an effective heating is obtained for pressing garments, the iron also being employed for therapeutic purposes in relieving pain when applied to affected parts of the human body.

This invention will be best understood from a consideration of the following detailed description, in view of the accompanying drawing forming a part of the specification; nevertheless, it is to be understood that the invention is not confined to the disclosure, being susceptible of such changes and modifications as define no material departure from the salient features of the invention as expressed in the appended claims.

In the drawing:

Figure 1 is a view in perspective of an iron

constructed in accordance with the principles of my invention.

Figure 2 is a vertical longitudinal section of the iron.

Figure 3 is a rear elevation of the iron.

Figure 4 is a horizontal section taken along the line 4—4 of Figure 2.

Figure 5 is a view in perspective of a removable plug for supporting an incandescent lamp within the iron.

Figure 6 is a view in perspective of the removable handle for the iron, and

Figure 7 is a view in perspective of a modified form of the iron which is particularly adapted for therapeutic purposes.

Referring more particularly to the drawing, 10 generally designates a hollow body which is formed of glass or any other suitable transparent material. This body is provided with a flat working surface 11, an inclined curved front portion 12 20 and the forward part of the iron is gradually reduced in cross sectional area to form a pointed portion 13 which is adapted to be moved forwardly between the folds of the goods which are adapted to be pressed. The rear portion of the 25 iron, as shown at 14, is substantially flat and is provided with an opening 15. The iron at this point has its greatest width.

The top 16 is curved downwardly towards the curved portion 12 at the forward end and is 30 provided with an internally threaded nipple 17.

A handle 18 has a threaded plug portion 19 which is screwed into the nipple 17. The handle extends rearwardly and terminates slightly beyond the rear wall 14. This handle, however, 35 is of sufficient length that it may be grasped securely by the hand of the operator. The outer end 19 of the handle is unconnected to the body of the iron so that the fingers may be freely moved beneath the handle from the rear.

A plug 20 formed of insulating material has a thread 21 of high pitch so that it is only necessary to insert the plug within the opening 15 and give it a slight turn for the threads 21 to be locked immediately with a complementarily 45 formed thread 22 formed at the inner wall of the opening 15.

The plug is provided with an axial bore 25 which is internally threaded to receive the threaded portion 26 of an electric lamp 27.

The lamp is provided with the usual filament 28 and is of sufficient power to create a temperature within the body for the purpose intended.

The plug 20 is formed of insulating material as is an extension 29 which has passages 30 and 31 to 50

receive, respectively, prongs 32 and 33 of a plug 34 of the usual type which is connected by electric wires 35 to the house current. It will be noted that the passages 30 and 31 extend through the extension 29, so that the prongs 32 and 33 may be inserted into the passages from either end. The purpose of extending the passages entirely through the plug is to permit the operator to readily insert the prongs in those ends of the 10 passages which are uppermost because when the operator replaces the bulb or lamp 27 by inserting the plug 20 and turning it he will not always return said plug to the former position so that if he starts to place the plug within the opening 15 at a point 180° from its former position the opposite ends of the passages 30 and 31 will appear at the top while the forward ends of the 15 passages will be located at the bottom. Thus it will be seen that the threads 21 are so constructed that the plug 20 may be screwed into the opening 15 at points 180° apart.

A threaded core 25, as shown in Fig. 2, is formed of metal and a conductor 35 extends from the core 25 and is adapted to engage the prong 25 33. A metal contact 36 engages the contact 37 on the lamp 27. A conductor 38 connects the contact 36 with a spring contact 39 which is adapted to be engaged by the prong 32.

The upper outer surface of the body, as shown 30 at 40, is covered with silver or some other suitable material which will act as a reflector for projecting the light rays from the lamp 27 on to the bottom 11 of the iron. The lower portion, however, is uncovered so that sufficient light rays will 35 be projected onto the goods for directing the operator in his work.

The inner surface of the bottom 11 is provided with a plurality of raised portions 41 which are so curved that they will form small lenses for concentrating the light rays and likewise the 40 heat rays through the bottom in order to increase the temperature at the bottom so that the bottom portion will be sufficiently heated for the purpose intended.

The device shown in Fig. 7 is constructed in an 45 identical manner with the device shown in Figs. 1 to 6, inclusive, except that the shape of the iron has been changed to make it more satisfactory for therapeutic purposes for applying the bottom 50 45 to some part of the human body when it is desired for the application of heat to an affected part. It will be seen that the corners 47 and 48 are rounded as is the blunt front portion 49. The side edges 50 of the iron are curved so that 55 no sharp points will at any time come in contact with the body.

It will be seen by this construction that the rays are not only reflected downwardly on to the bottom 11 of the iron or the bottom 45 of the 60 device for therapeutic purposes by the reflector 40 but the semi-spherical projections 41 on the inner surfaces of the bottom of each of the devices will concentrate the rays on to the work or on to some part of the human body which is adapted 65 to be treated so that substantially all of the heat developed by the filament 28 may be efficiently utilized.

The handle is removably connected to the body so that when it is desired to pack the iron in a 70 suitcase the handle may be removed and thus reduce the space required for storing the iron.

I claim:

1. An iron comprising a hollow body formed of transparent material and having an opening at one end, a plug threaded into said opening and provided with contacts for connection with an electric circuit, an electric lamp electrically connected with the contacts and supported by the plug, ray concentrating means on the bottom of the body, and a thin metallic covering on the upper outer surface of the iron for reflecting rays 10 on to the ray concentrating means.

2. An iron comprising a hollow body formed of transparent material and having an opening at one end, a plug threaded into said opening and provided with contacts for connection with an electric circuit, an electric lamp electrically connected with the contacts and supported by the plug, and ray concentrating means on the bottom 15 of the body.

3. An iron comprising a hollow body formed of transparent material and having an opening at one end, a plug threaded into said opening and provided with contacts for connection with an electric circuit, an electric lamp electrically connected with the contacts and supported by the 25 plug, and a thin metallic covering on the upper outer surface of the iron for reflecting rays on to the ray concentrating means.

4. An iron comprising a hollow body formed of transparent material and having an opening at 30 one end, a plug threaded into said opening and provided with contacts for connection with an electric circuit, an electric lamp electrically connected with the contacts and supported by the 35 plug, ray concentrating means on the bottom of the body, and a reflector at the upper portion of the body.

5. A sad iron comprising a hollow body formed of transparent material and having a flat bottom and an opening at one end, a plug threaded into 40 the opening and provided with contacts for connection with an electric circuit, an electric lamp removably supported by the plug and having electrical connections with the contacts, the inner face of the bottom being provided with a 45 plurality of lenses for concentrating the rays at the outer surface of the bottom.

6. A sad iron comprising a hollow body formed of transparent material and having a flat bottom and an opening at one end, a plug threaded into 50 the opening and provided with contacts for connection with an electric circuit, an electric lamp removably supported by the plug and having electrical connections with the contacts, the inner face of the bottom being provided with a plurality 55 of lenses for concentrating the rays at the outer surface of the bottom, and means reflecting the rays on to the lenses.

7. A sad iron comprising a hollow body formed of transparent material and having a flat bottom and an opening at one end, a plug threaded into 60 the opening and provided with contacts for connection with an electric circuit, an electric lamp removably supported by the plug and having electrical connections with the contacts, the inner face of the bottom being provided with a plurality 65 of lenses for concentrating the rays at the outer surface of the bottom, and a metallic coating covering the top and a portion of the side walls of the body for reflecting rays on to the lenses.

BENJAMIN A. KAPLAN.
